WILLIAM J. BRADLEY, OF TROY, NEW YORK, ASSIGNOR TO MONARCH STEAM BLOWER COMPANY, OF TROY, NEW YORK, A CORPORATION.

SOOT-CLEANER FOR STEAM-BOILERS.

1,037,422.

Specification of Letters Patent. Patented Sept. 3, 1912.

Application filed September 28, 1911. Serial No. 651,752.

To all whom it may concern:

Be it known that I, WILLIAM J. BRADLEY, a citizen of the United States, residing at Troy, county of Rensselaer, and State of New York, have invented certain new and useful Improvements in Soot-Cleaners for Steam-Boilers, of which the following is a specification.

The invention relates to such improvements and consists of the novel construction and combination of parts hereinafter described and subsequently claimed.

Reference may be had to the accompanying drawings, and the reference characters marked thereon, which form a part of this specification.

Similar characters refer to similar parts in the several figures therein.

Figure 1 of the drawings is a view in side elevation showing my invention applied to a water-tube boiler, the brickwork of the boiler-setting being partly broken away. Fig. 2 is a horizontal section of the same taken on the broken line 2—2 in Fig. 1, along one side of the boiler-setting. Fig. 3 is a vertical cross-section taken through the axis of one of the nozzle-carrying pipes showing at the upper end in detail the self-sealing rotative connection between said pipe and the steam-box from which it receives a supply of steam, and showing at the lower end in detail the bearing for the lower end of said pipe and the gear whereby said pipe is rotated. Fig. 4 is a cross-section taken on the broken line 4—4 in Fig. 3, through the bearing-box for the lower end of a nozzle-carrying pipe, showing a bottom plan view of the lower end of the pipe and its operating-mechanism. Fig. 5 is a cross-section taken on the broken line 5—5 in Fig. 3. Fig. 6 is a cross-section taken on the broken line 6—6 in Fig. 3, showing a top plan view of the steam-box and its supply-pipe. Fig. 7 is a view in vertical section of the bearing for the lower end of the nozzle-carrying pipe, showing the lower portion of said pipe and its operating-mechanism in side elevation.

My invention relates to a type of soot-cleaner for steam-boilers wherein jets of steam are projected into or through the draft-space by nozzles carried by a rotatively mounted pipe whereby said nozzles can be swung into and out of position for

use. In boiler-cleaners of this type, considerable difficulty is experienced in operating the nozzle-carrying pipe and also in maintaining a steam- or gas-tight rotative connection between the nozzle-carrying pipe and the steam-box from which the pipe is supplied, due to the excessive heat to which said pipe is exposed in the furnace structure.

The present invention relates more particularly to the mounting of such pipes whereby their efficiency and operation are not affected by high degrees of heat or by excessive changes in temperature.

The principal object of the invention is to provide for maximum expansion of such a pipe and the parts co-operating therewith, while maintaining a tight joint between the pipe and the steam-box whereby it is supplied, as well as full operative relationship between said pipe and the mechanism whereby the same is rotated.

The invention is applicable to various types of steam-boilers and is particularly adapted for use in water-tube boilers as shown in the accompanying drawings.

Referring to the drawings wherein the invention is shown in preferred form, 1, represents the brickwork setting for a water-tube boiler having tubes, 2, communicating at their opposite ends with water-legs, 3 and 4, said water-legs connecting with the cylinder, 5, in the usual manner.

The flue-space across which the water-tubes extend, is subdivided by vertical baffle-plates, 6, into a plurality of sections, whereby heated gases, in passing from the furnace to the stack, are caused to cross the line of water-tubes in different directions. Housed in the brickwork setting along the side of the boiler opposite each of the sections into which the draft-space is thus subdivided, is a pipe, 7, which extends in a vertical plane, and is preferably inclined at approximately right angles to the water-tubes. The pipe, 7, is provided at intervals which preferably correspond with the intervals between neighboring rows of water-tubes, with nozzles, 8, adapted in certain rotative positions of the pipe, 7, to direct jets of steam or air issuing therefrom more or less directly across the draft-space and between and against the water-tubes. The

pipe, 7, is rotatively supported at its upper and lower ends by suitable bearings. The bearing for the upper end of the pipe, 7, comprises a ball-and-socket ground joint, one member, 9, of which is fixed upon the tube, and the other member of which is formed by an interior annular shoulder, 10, on the steam-box, 11, surrounding an opening through which the tube, 7, extends. A free space is left within the steam-box 10 above the bearing-members to permit maximum expansion of the parts, the joint being rendered effective wholly by gravity and the internal pressure within the steam-box. The steam-box is provided in its top in line 15 with its bottom aperture through which the pipe, 7, extends, with a larger aperture, 12, adapted to freely permit the passage therethrough of the pipe, 7, and its bearing-member, 9, which opening is closed by a screw-plug, 13, which can be removed to permit the insertion or removal of the pipe. The curved bearing-surfaces on the ball-and-socket members, 9 and 10, are ground to 20 accurately fit one another, whereby, for the purposes of this invention, they are adapted to form a tight joint under the internal pressure within the steam-box in different rotary positions of the pipe, 7, as well as in such different relative angular positions 25 as the bearing-members may be caused to assume, due to deflection of the pipe or unequal expansion of the parts when exposed to the high temperature to which such pipes are subjected in use. The bearing for the 30 lower end of the pipe, 7, is formed in a bearing-box, 14, which is adapted to rotatively support the pipe while freely permitting maximum expansion of the same. The bearing-member on the lower end of the pipe, 7, is formed by the cylindrical hub, 15, of the gear, 16, whereby rotary movements are imparted to the pipe 7. The hub, 15, fits within an opening in the bearing-box, 14, through which opening it is adapted 35 to reciprocate in accordance with variations in the length of the pipe, 7, due to expansion and contraction. The teeth of the gear, 16, are confined within and preferably 40 correspond with the cylindrical dimensions of the hub, 15, whereby said gear is adapted to pass through and occupy the bearing-opening in the bearing-box 14. The gear, 16, is engaged by a gear-segment, 17, rotatively mounted at, 18, upon the underside of 45 the top of the bearing-box, 14, and provided with an operating-handle 19. The longitudinal extent of the teeth of the gear, 16, is such that when the pipe, 7, is fully contracted, the upper ends of the gear-teeth enter and are located within the bearing-opening in the top of the bearing-box, 14, as shown in Fig. 3, thus providing for sufficient lost motion to permit maximum expansion of the pipe, 7, without bringing the

hub, 15, of the gear into contact with the gear-segment 17. The gear, 16, thus remains constantly in full operative engagement with the gear-segment, 17, under all of the varying conditions of temperature to 70 which the device is subjected in use.

It will be understood that the pipe, 7, is unconfined and unrestricted as to longitudinal movement, except by the ball-and-socket bearing, 9 and 10, whereby said pipe is suspended in position so that said pipe is free to yield to the varying conditions of temperature without interfering with its capability for rotation, and without impairing the joint formed between the pipe and the 80 steam-box.

The steam-box may be connected with any convenient source of supply, which may be steam or air under pressure. As shown, the several steam-boxes are connected with 85 a common supply-pipe, 20, connecting with the steam-space of the boiler and controlled by a valve 21.

In cleaning the boiler, the steam pressure is admitted to the steam-boxes through the 90 pipe, 20, and the several nozzle-carrying pipes, 7, are rotatively moved by means of the gear-mechanism operated by the handle, 19, causing the jets issuing from the nozzles, 8, to be projected into the draft-space and 95 between and against the water-tubes to remove accumulations of soot, &c., as is well understood in the art.

The steam-box, 11, and the bearing-box, 14, are connected together and supported by 100 means of stay-rods, 22, which pass through suitable apertures in said bearing-box and in the flanges, 24, on said steam-box, said rods being secured to said flanges and said bearing-box by means of nuts, 25, screwed 105 upon the threaded ends of said rods. The stay-rods, 22, are embedded in the brick-work of the boiler-setting.

What I claim as new and desire to secure by Letters Patent is—

1. In a device of the class described, and in combination, a box provided with a bottom-opening; means for supplying to said box fluid under pressure; a pipe rotatively mounted in said opening, said pipe and box 110 having coöperating ball-and-socket bearing-members whereby said pipe is suspended from said box through the bottom opening therein; means for rotating said pipe; and nozzles carried by said pipe.

2. In a device of the class described, and in combination, a box provided with a bottom-opening; means for supplying to said box fluid under pressure; a pipe rotatively mounted in said opening, said pipe and box 115 having coöperating ball-and-socket bearing-members whereby said pipe is suspended from said box through the bottom opening therein; means for rotating said pipe; nozzles carried by said pipe; and a bearing ro- 120

125

130

tatively supporting the lower end of said pipe, said bearing affording a free space for maximum expansion of said pipe.

3. In a device of the class described, and in combination, a pipe rotatively supported at one end; means for supplying to said pipe fluid under pressure; a bearing-box provided with a cylindrical opening; a gear-member rotatively mounted adjacent to the outer end of the opening in said bearing-box; and a gear and hub fixed upon the other end of said pipe, said hub being adapted to occupy the cylindrical opening in said bearing-box, and the teeth of said gear being confined within the cylindrical dimensions of said hub, and when said pipe is fully contracted being located partly within said cylindrical opening, said teeth being longitudinally extended to properly engage said gear-member when said pipe is under maximum expansion.

4. In a device of the class described, and in combination, a box provided with a bottom-opening; means for supplying to said box fluid under pressure; a pipe rotatively mounted in said opening, said pipe and box having co-operating ball-and-socket bearing-members whereby said pipe is suspended from said box through the bottom-opening therein; means for rotating said pipe; nozzles carried by said pipe; a bearing-box provided with a cylindrical opening; a gear-member rotatively mounted adjacent to the outer end of the opening in said bearing-box; and a gear and hub fixed upon the lower end of said pipe, said hub being adapted to occupy the cylindrical opening in said bearing-box, and the teeth of said gear being

confined within the cylindrical dimensions of said hub, and when said pipe is fully contracted being located partly within said cylindrical opening, said teeth being longitudinally extended to properly engage said gear-member when said pipe is under maximum expansion.

5. In a device of the class described, and in combination, a steam-boiler and boiler-setting; a rotatory pipe mounted in the boiler-setting; nozzles carried by said pipe, the boiler-setting being provided opposite the respective nozzles with suitable apertures communicating with the draft-space of the boiler; a bearing-box for one end of said pipe; a steam-box forming a bearing for the other end of said pipe; and supporting members embedded in the boiler-setting and connected at their opposite ends, respectively, with said bearing-box and said steam-box.

6. In a device of the class described, and in combination, a steam-boiler and boiler-setting; a steam-box; a pipe rotatively suspended from said steam-box by means of a suitable bearing; a bearing-box for the lower end of said pipe affording a free space for maximum expansion of said pipe; supporting-members embedded in the boiler-setting and secured at their opposite ends, respectively, to said steam-box and said bearing-box; and nozzles carried by said pipe.

In testimony whereof, I have hereunto set my hand this 21st day of September, 1911.

WILLIAM J. BRADLEY.
